STIFFENED ROLL COLLAR

Jacob V. Cohn, Detroit, Mich.

Application January 9, 1948, Serial No. 1,409

5 Claims. (Cl. 2—132)

1

This invention relates to a collar for an article of apparel. More particularly it relates to collars for shirts.

This invention is an improvement on the inventions in application Nos. 777,517, filed October 2, 1947, and 783,807, filed November 3, 1947 which applications matured into United States Letters Patent Nos. 2,500,910 of March 14, 1950, and 2,500,911 of March 14, 1950, respectively, to the same inventor.

The first portion of a clean shirt to become mussed or show signs of wear is the collar. Collars become wrinkled, curled and dirty before the other portions of the shirt because they are exposed more to the atmospheric conditions and to perspiration from the neck of the wearer. The collars are also apt to become wrinkled because of the frequency with which the collar is bent due to movement of the head and neck of the wearer, etc. To improve the resistance of the collar to wrinkling, wilting, etc. various means have been suggested and employed. For example, "fused" collars which comprise a layer of laminated fabrics made by uniting two or more pieces of fabrics by means of thermoplastic threads or materials have been suggested and are used extensively. Even with this type of collar the points of the collar will curl and become otherwise distorted. To overcome curl in the points of the collar it has also been proposed to provide for the insertion of removable stays in the collar points. For example, a slot is provided on the under surface of the collar points and small strips of relatively stiff material such as Celluloid is provided to be inserted in the slots during wearing. These stays must be removed during laundering and are often lost. Furthermore, they are sometimes difficult to insert in a freshly laundered shirt and so ordinarily they are left out by the wearer.

Recently the roll type of collar has become popular in the trade. Aside from different style effects which it produces the roll collar has certain other advantages such as not being easily distorted by a heavy tie and being very well adapted to be worn either open as a sport shirt or closed as a dress shirt. With roll collars the points of the collar are ordinarily made longer than usual so that there is more of the point to curl. The "roll" referred to is a convex outward curve in the collar between the neck band and the points.

In applications Nos. 777,517 and 783,807 which matured into United States Letters Patent Nos. 2,500,910 and 2,500,911, both of March 14, 1950,

2

respectively, referred to above there has been disclosed several constructions of roll collars in which the roll of the collar is inherent in the collar construction and is not dependent on the addition of stays or other similar structures. In application No. 777,517 which matured into Patent No. 2,500,910 of March 14, 1950, the roll is produced by incorporating into the collar a triangular type of insert at each of the points or wings of the collar. In application 783,807 which matured into Patent No. 2,500,911 of March 14, 1950, the roll is produced by incorporating a single insert which has bias cut ends simulating the triangular cut inserts of application No. 777,517 which matured into Patent No. 2,500,910 of March 14, 1950. These same types of inserts are incorporated according to the present invention and will be described more in detail below.

If a fabric (especially a plain woven fabric) is stretched in a direction diagonal to the direction of the threads of the warp to woof, it will be noted that there is a tendency for the fabric to wave or curl. The curvature produced is usually in two directions. However, if a small piece of a fabric is cut on a bias or diagonal with respect to the direction of the threads then a small amount of tension applied diagonally to the threads will cause it to curl in only one direction. It is upon this phenomenon that the roll effect of the inventions referred to above depends. The inserts are so cut and placed in the collar that the direction of greatest strength of the insert is parallel to the neck line or neck band of the collar.

In the production of dressy or stiffer collar it is not an unusual practice to unite or laminate (by sewing or otherwise) the fabric which is to form the outside of the collar with a liner fabric (usually of heavier, coarser and cheaper material). When the bias cut inserts of the above cited inventions were combined with such collar parts however it was found that the roll effect was considerably reduced.

This reduction in roll effect was found to be due to the fact that the lining material of the collar was cut with the direction of greatest strength along the neck line or length of the collar. The roll-producing insert and the lining material for the outside of the collar were therefore cut with their direction of greatest strength coinciding and since the lining material is not cut on a bias adjacent the points of the collar, it resists the tendency of the bias cut insert to produce a unidirectional roll in the collar. The

heavier or stiffer the lining material the more it resists the roll effect of the bias cut insert.

An object of this invention is to produce a relatively stiff roll collar with a smooth even curvature and a natural roll.

Another object of the invention is to provide a lined roll collar which has superior resistance to crushing and wrinkling when worn.

Another object of the invention is to produce a reinforced roll collar which has superior resistance to wilting due to perspiration and superior resistance to undesirable curling of the points of the collar.

Another object of the invention is to produce a reinforced roll collar which is adapted to conform to the neck of the wearer and which can be adjustably opened or closed by adjusting the tie which is worn.

These objects and others ancillary thereto are obtained by including in the collar construction a flexible but stiff bias-cut fabric insert and a lining material substantially coextensive with the outside of the collar but cut with the direction of greatest strength diagonal to the neck line of the collar. The insert is made of interlining material. At the edge of each wing of the collar the insert extends between the point of wing and the neckband of the collar. It may extend into and be anchored as by sewing in the neckband. The insert does not extend into the outside portion of the back of the collar or in other words at the part intermediate the collar points or wings, although, if desired, the insert may extend all around the neckband part of the collar. At some area relatively near the points, the insert or inserts are cut on a bias sloping away from the points. The edge portions of the insert may be sewed to the lining and/or outside fabric of the collar. The bias cut edges may be unattached to the remainder of the collar or they may be sewed to the inside or liner portion of the collar.

The insert is made of interliner fabrics or similar material. Various types of interliner fabrics may be employed. Directionally stiff interliner material, i. e., fabrics which are stiffer in the direction of the warp than in the direction of the woof or filler threads, or vice versa, may be employed. Or interliner fabrics which are fairly stiff in the direction of both warp and woof may be employed. Fabrics may be made more flexible in one direction than in the other by making the warp or the woof at least partly of animal fibers such as mohair, Angora goat, wool, casein wool, or horsehair while employing cotton, vegetable fibers for the fibers in the opposite direction. Nylon and silk can also be employed for the fibers in one direction. It is also possible to increase or decrease the stiffness of the warp or woof of a fabric by treating with a chemical which affects one set of parallel fibers while being inert to the other set of fibers. For example, the filler fibers may contain thermoplastic or soluble fibers such as fibers cellulose acetate, copolymers of vinyl chloride and vinyl acetate, vinylidene chloride, etc. and these fibers can be stiffened by treatment with solvents.

As heretofore indicated, it is important to pay particular attention to the alignment of the threads in the bias cut insert. The insert is cut so that its direction of greatest resistance to stretching is at least approximately along a line parallel to the neckband of the collar. The line of greatest stretchability or flexibility is diagonal with respect to the direction of greatest resistance to stretch and is there-

fore approximately parallel to the bias or diagonal edge of the insert. There is therefore a pronounced tendency for the insert to produce an even roll in the collar when it is stretched or extended. Thus, by manipulating the collar, as when ironing after washing, the insert can be extended in the direction of its greatest extensibility and owing to the increased resistance to stretching along the warp or woof of the fabric the insert will curve about an axis parallel to the direction of the stretch. This tendency to curve or curl when extended along a line diagonal to the warp or woof will be noted in any fabric, particularly in any plane woven fabric. Interliner fabrics are so constructed as to produce stiffness while also having flexibility. When the flexibility is greater along one set of threads (the warp or the woof) than along the other set, and when the insert is made with the direction of greatest stiffness parallel to the neckband, then the direction of greatest flexibility is in the direction of the roll of the collar and a neat, draped, roll effect is produced. When a rectangularly shaped fabric is stretched diagonally, there is a tendency for the fabric to curl back and forth in two directions but by cutting the fabric diagonally or along a bias, this tendency to curl or roll in two directions is avoided.

The lining material which substantially fully covers and stiffens the inner side of the outer part of the collar is cut so that its direction of greatest strength is diagonal to the neckline. In other words the direction of greatest strength of the bias-cut insert and the direction of greatest strength of the lining fabric are substantially perpendicular to each other. This is an awkward and unusual way to cut the lining material as it involves cutting the liner diagonally to the running length of the fabric from which it is cut. It has been the practice to cut such liner blanks with the length of the blank either parallel or perpendicular to the length of the fabric as these are the simplest and easiest ways to cut such blanks. It has now been found, however, that the extra trouble necessary to cut the liner blanks on a bias is more than compensated for in the improved results obtained. In fact a slight roll effect is produced by such a collar with a criss cross or diagonal cut liner even in the absence of the triangular or similar inserts.

The diagonal cut liner may be made from ordinary types of liner fabrics employed in collars. The same materials employed for the bias cut inserts may also be employed for the coextensive liners. By cutting the liner in the new way it is possible to employ much heavier fabrics for liners than heretofore because the liner stiffens the collar in a direction that is not uncomfortable to the wearer.

The stiffened collar of the present invention does not require that it be buttoned at the neck line. The roll produced makes the collar conform to the neck of the wearer even when the button is placed below the neck band or what would ordinarily be the neck band of the collar.

The novel features characteristic of this invention are set forth with particularity in the appended claims. The invention itself, however, both as to its organization and its method of operation, together with additional objects and advantages thereof, will best be understood from the following description of specific embodiments when read in connection with the accompanying drawing in which:

Figure 1 is a perspective view partly cut away

of a shirt containing the collar of the invention.

Figure 2 is a detailed view of one of the collar points.

Figure 3 is a detailed view of the insert.

Figure 4 is a perspective view of a collar with another type of insert.

Figure 5 is a detailed view of one of the collar points of Figure 4.

Figure 6 is a view showing the coextensive liner material with a triangular type of insert thereon.

Figure 7 is a view of a triangular type of roll producing insert.

Figure 8 is a perspective view showing a portion of a shirt with a roll collar made according to the present invention and with the top button below the neck band of the shirt.

Figure 9 is a view showing how the collar liner is cut from a length of liner fabric.

In Figure 1 the collar 3 is shown attached to the shirt 1 and the collar is closed, in the drawing, by the button 2. As shown in the drawing the collar from an area adjacent the button 2 to the points 4 or 5 has a convex curvature with respect to the remainder of the shirt. This curvature is greatest close to the neckband adjacent the parts numbered 22 and 23. Although the collar is shown attached to a dress shirt it is obvious that it may be attached to any type of sport or dress shirt whether they may be men's, boys' or ladies' shirts. The collar may also be employed in the manufacture of jackets, coats, sweaters and any type of garment which employs a collar.

The collar itself is substantially the same as the ordinary collar except for the insert heretofore referred to and shown at 12 in the drawing and the lining fabric 50 which is coextensive with the outside of the collar. The collar shown comprises an outside fabric 10 (which may be of the same material as the shirt or may be the shirt material combined or fused to a stiffening fabric), a coextensive liner 50, a backing 11 and the insert 12. The parts of the collar are attached together in the usual way as for example by the stitches 13.

The insert comprises two end portions 31 and 32 adapted to extend into the points or wings of the collar and a narrow intermediate portion 33 which is equal to or slightly greater than the width of the neckband at the back of the shirt. One edge of each of the wings 31 and 32 of the insert is continuous with an edge of the intermediate portion 33 along the liner 34 and this edge 34 is parallel to the edge of the collar where the collar is attached to the shirt. The edges 36, 37, 38 and 39 are also cut to substantially coincide with edges of the finished collars. The edge 35 of the intermediate portion is connected to the edges 38 and 39 respectively by the bias or diagonal cut edges 40 and 41. The part of the insert which coincides with the edges of the collar may be sewed to the collar by a kind of French seam type of stitch 13 or its equivalent. The bias cut edges 40 and 41 of the insert are preferably sewed to the under part 11 of the collar as shown at 42 but the stitches do not extend through the outside fabric 10. The bias cut edges 40 and 41 may be left unattached to the remainder of the collar.

The point on the edge 27 of the collar from which the bias cut edges 40 or 41 begins to slope toward the intermediate portion 33 of the insert may be varied depending on the style, size of wings or other features desired in the collar.

In the insert shown in Figure 3 the direction of greatest strength is along the line 51-51 and this line 51-51 will form the top of the collar (as nearly as the top of a roll collar can be determined). The line 51-51 is parallel to the warp threads 52 of the fabric. The woof threads 53 will preferably contain animal fibers such as horsehair, Angora goat wool, or casein wool so as to give the fabric a slightly greater extensibility in the direction of the woof 53 than in the direction of the warp 52.

The liner blank 59 is cut from a fabric 70 with the direction of the threads (and the direction of greatest resistance to stretch) diagonal with respect to the length of the collar as shown in Figure 9. The liner is preferably attached to the inside portion of cloth which is to form the outer part of the collar although if desired it could be attached next to the under portion 11 of the collar.

Figures 1-3 show the type of bias-cut, roll-producing insert 12 which is described and claimed, per se, in application No. 783,807, filed November 3, 1947, which matured into Patent No. 2,500,911 of March 14, 1950, while Figures 4, 5 and 7 show the bias cut insert which is similar to that described and claimed in application No. 777,517, filed October 2, 1947, which matured into Patent No. 2,500,910 of March 14, 1950, in which the present applicant is the inventor.

In Figures 4-7, the like parts are numbered as in Figures 1-3. The collar 3 of Figures 4 and 5 is substantially the same as the collar of Figures 1-3 except for the shape of the bias-cut, or roll-producing inserts 60. The collar is made with the outside shirt fabric 10, the liner 50 which is substantially coextensive with the outside fabric 10, the inner fabric 11 and with a separate bias cut insert 60 in each point or wing. The inserts 60 are not connected with each other as in Figures 1-3. The front side of the insert is attached at 13 to the front edge of the wing; the side 62 is attached to the lower edge of the collar and the edge 64 is attached at the neck line of the shirt. The bias cut side 63 may be left unattached (as shown) to the remainder of the collar or it may be sewed to another part of the collar, as, for example, the under side 11.

Figure 7 shows a triangular type of insert of a slightly different shape. This insert 69' has straight sides 61', 62' and 64' and a slightly curved side 63'. In this type of insert the sides 63' and 62' may in fact be merged into a single side and at times it has been convenient to refer to this type as a triangular insert.

Figure 6 shows how the insert 60' of Figure 7 may be superposed on or combined with the coextensive liner 50 of the collar. Preferably there are narrow borders 51 and 52 on the liner 50 which extend beyond the edges 61 and 62 of this biased insert, to allow for the usual seam formation (a French type of seam) in the collar.

Figure 8 shows a very adaptable type of shirt collar which is conformable to the neck of the wearer and yet is not fixed tightly about the neck. By employing the roll effect in the collar the upper part of the collar clings loosely about the neck of the wearer in spite of the fact that the top button is placed below the neckband or what would ordinarily be the neckband of the shirt. A roll collar of the type disclosed is conformable to the neck even without the addition of the coextensive interliner, but by the addition of the interliner 50 (and especially

75 when the latter is made of relatively stiff ma-

aterial) this type of shirt becomes extremely attractive and practical.

Contrary to expectations it has been found that after laundering the shirt the roll of a collar having the biased inserts therein is actually improved. In fact, almost any manipulation of the collar such as ironing or working with the fingers, etc. causes the insert to produce a more pronounced roll.

It will be seen that this invention provides a stiffened roll type of collar which has a smooth even roll or curvature which is more resistant to wilting and crushing than collars of the ordinary type.

When a fabric is used for the making of the biased insert which would have a likelihood of unravelling in the course of its use and laundering, it is desirable to enclose the fabric or treat it to prevent such unravelling. For example, the insert may be enclosed in other cloth in any suitable way, as for example by covering the insert with a fabric and stitching the covered material to the fabric in some suitable manner.

Alternatively the exposed edges of the biased inserts may be protected by means of a fabric folded over the marginal exposed areas and stitched thereto as for example one-quarter inch in from the edge. The covered material which thus protects the insert against ravelling not only does not impair the roll effect obtained by the insert but may improve that roll effect.

As a further alternative for the protection of either or both of the biased and coextensive inserts against unravelling, the exposed cut edges of the inserts may be coated with a plastic material which acts to bind these exposed edges and prevents their unravelling. A suitable plastic material is for example, a cellulosic lacquer, such as cellulose acetate in a solvent, which is applied to the edges of the insert by dipping the insert in a solution or by brushing the plastic solution on the edges. Upon drying the plastic sets and binds the exposed cut edges of the insert, thus preventing unravelling.

Although certain specific embodiments of this invention have been shown and described, it will be understood that many modifications thereof are possible. This invention, therefore, is not to be restricted except insofar as is necessitated by the prior art and by the spirit of the appended claims.

I claim:

1. In a garment with a roll, fold-over collar of the type having an opening at the front and two wings or points extending from the opening, in which each of said wings extend upwardly from the opening and then downwardly and outwardly to form a top edge of the collar, the improved construction which comprises, an outside fabric, a liner fabric substantially coextensive with said outside fabric, an insert consisting of fabric material which is relatively extensible in the diagonal direction with respect to the threads thereof having one side extending along and substantially coextensive with the front edge of one of the wings, said side being attached to the collar along a line adjacent to said edge and a second side extending and attached parallel to the top edge of said collar, and said insert having a third side which is cut on a bias and extends from a point adjacent the corner of the wing diagonally

away from the corner and toward the said top edge of the collar, said insert being cut so that the direction of one series of its crossed threads is parallel to the top edge of the collar, said coextensive liner being cut so that the direction of greatest strength of the fabric from which it is cut is substantially diagonal with respect to the top edge of the collar.

2. In a garment with roll, fold-over collar of the type having an opening at the front and two wings or points extending from the opening, in which each of said wings extend upwardly from the opening and then downwardly and outwardly to form a top edge of the collar, the improved construction which comprises an outside fabric, a liner fabric substantially coextensive with said outside fabric, a flexible fabric insert having one side extending along the front edge of one of the wings from the said opening to the corner thereof, said side being attached to the collar adjacent said edge and a second side extending and attached parallel to the top edge of said collar, and said insert having a third side which is cut on a bias and extends from a point adjacent the corner of the wing diagonally away from the corner and toward the said top edge of the collar, said insert being cut so that the direction of greatest strength of the fabric is parallel to the top edge of the collar, said coextensive liner being cut so that the direction of greatest strength of the fabric from which it is cut is substantially perpendicular with respect to the direction of greatest strength of the bias-cut insert.
3. The collar as set forth in claim 2 in which both wings contain said bias cut inserts which are separate, said collar having a neckband substantially parallel to the top edge thereof, the second side of said inserts extending into and being attached to the neckband.
4. The collar as set forth in claim 2 in which both wings contain said bias cut inserts, said collar having a neckband substantially parallel to the top edge thereof, the second side of said inserts extending into and being attached to the neckband, said inserts being attached to each other by a narrow strip of material adjacent the neckband of said collar.
5. The collar as set forth in claim 2 in which both wings contain said bias cut inserts, said collar having a neckline substantially below and parallel to the top edge thereof, the second side of said inserts extending to a point below the neckline, a means to fasten the opening of said collar, said means being located below the neckline of said collar whereby the said inserts and the said fastening means cooperate to produce a roll collar with an adjustable distance between the wings.

JACOB V. COHN.
